UNITED STATES PATENT OFFICE.

AUSTEN M. CURTIS, OF EAST ORANGE, NEW JERSEY, ASSIGNOR TO WESTERN ELECTRIC COMPANY, INCORPORATED, OF NEW YORK, N. Y., A CORPORATION OF NEW YORK.

ELECTRIC-CURRENT TRANSMISSION.

Continuation of application Serial No. 58,741, filed September 26, 1925. This application filed December 7, 1925. Serial No. 73,574.

This invention relates to electric current transmission systems and to amplifiers and circuits for association therewith, and aims for simplicity and efficiency in transferring 5 signals between an amplifier and a circuit for connection to the amplifier input or output, especially where disturbance due to undesired currents, such for instance as currents resulting from the tendency of the 10 amplifier to oscillate and from voltages induced in the system by extraneous sources, should be guarded against; and more especially where direct current or other very low frequency current is to be transmitted 15 between the amplifier and the circuit or the use of a transformer for connecting the amplifier to the circuit is objectionable.

In accordance with the invention, substantially the whole of the signal voltage 20 across either the amplifier or the circuit may be transmitted to the other without necessitating the employment of a transformer, and yet disturbances due to voltages impressed on the line from extraneous sources 25 and to the tendency of the amplifier to oscillate are prevented, without seriously impairing the transmission efficiency of the system for the signals.

The amplifier may be directly connected 30 to the circuit, for instance a twin conductor cable balanced as regards the impedances of its conductors to earth, without disturbing such balance, and without seriously reducing the efficiency of the amplifier or of the 35 cable, and at the same time the amplifier is effectively stabilized with relation to its surroundings for the higher frequencies, at which oscillation might occur were the amplifier not so stabilized. The direct connection 40 of the amplifier to the cable avoids any necessity for a connecting transformer which might be difficult to design and construct.

It is also an object of the invention to reduce 45 disturbance in a system in which signals are transferred through two circuits that are connected by an amplifier and exposed to interference from extraneous electric fields.

The invention permits signals to be transferred 50 from one two-conductor balanced cable, by means of an effectively earthed

space discharge amplifier, to a second balanced cable, without permitting either cable to be unbalanced by the amplifier or by the 55 other cable, and enables this to be done with only one transformer in the amplifier circuit. It also allows an effectively earthed amplifier to be directly connected to a two-conductor balanced cable without the use of 60 a transformer and without destroying the balance to earth of the two conductors of the cable.

In accordance with the invention an electric space discharge amplifier which connects an incoming circuit that has its two sides balanced, with respect to their impedances between ground and the amplifier, to an outgoing circuit balanced as regards the 65 impedances of its two sides to ground, is stabilized, and at the same time interference effects due to the action of extraneous electrical fields upon either circuit is minimized by preventing either circuit from being unbalanced by the amplifier or the other circuit, even though the impedance to ground of each circuit be such as to be capable of 70 materially unbalancing the other circuit were that impedance connected to the two conductors of that other circuit asymmetrically with respect to those two conductors, 75 for instance as a result of conductive connection of each circuit to the space discharge device of the amplifier.

In the forms of the invention specifically 80 described hereinafter by reference to the accompanying drawing, a space discharge amplifier with a cathode, anode and control electrode has its cathode connected to one side of a circuit with which it is to be associated and one of the other electrodes connected to the other side of the circuit, and the end of the circuit adjacent the amplifier is shunted by a circuit comprising two condensers in series, the junction point of the 85 condenser being grounded. The amplifier is thus earthed locally through one of the condensers, which has sufficient capacity to effectively earth the amplifier for frequencies at which it might tend to oscillate, and at the same time, the balance of the circuit 90 associated with the amplifier, as regards the impedances of its two sides to earth, is maintained.

In one of the forms of the invention shown in the drawing, the amplifier having an input set and an output set of electrodes is stabilized and has one of the sets of electrodes associated with one circuit, for instance a land cable of substantial length, in the manner just described, and has the other set of electrodes non-conductively associated with another circuit, for instance a submarine cable circuit with a balancing return path including an interference reducing conductor, by a transformer, which transmits signals between the submarine cable circuit and the amplifier but prevents either cable from being unbalanced by the amplifier or the other cable, and thereby minimizes deleterious effects of interference due to extraneous fields to which the land cable or the amplifier end or shallow water section of the sea cable may be exposed.

Other objects and advantages of the invention will be apparent from the following detailed description in connection with the accompanying drawing, wherein each of the figures illustrates an application of the invention in submarine cable telegraphy, although it is not limited to such application. Fig. 1 is a circuit diagram showing a way in which the invention can be applied to the connection of the output of an amplifier to a circuit, and also a way in which the invention can be applied to the stabilization of an electric space discharge amplifier and the connection of the amplifier between two circuits in such manner as to prevent either circuit from being unbalanced by the stabilized amplifier or by the other circuit; and Fig. 2 is a circuit diagram showing a way in which the invention can be applied to the connection of a circuit to the input of an amplifier.

The cable systems herein described are adapted for use with submarine cables of such great length, as transoceanic cables for example, that signals arriving from the cable are greatly attenuated, and, even after shaping and amplification, may be almost completely masked by extraneous disturbances unless some means are provided for effectively reducing the effect of disturbing magnetic fields upon the cable. Such means may, however, become of use in other types of signaling systems as the severity of operating conditions increases.

In the drawing, 1 is intended to represent a cable, for example a loaded submarine cable having large distributed capacity, inductance and resistance, and 2 is intended to represent a direct amplifying type of electric space discharge amplifier for receiving telegraph signals from the cable 1 and transmitting them through a circuit 10 to a receiving device 12, for instance a siphon recorder. The term "direct amplifying type" is used in the specification and claims to define an amplifier that increases the energy

of an electric wave without shifting or converting the frequency of the wave before, during, or after amplification.

The cable 1 comprises a single core section 3 terminated in a twin core section 4. One core 5 of the twin core section 4 is connected at one end to the single core section 3 and at the other end to one terminal of signal receiving apparatus which comprises shaping network 19, input transformer 20 and amplifier 2 and which will be presently described. The other terminal of the receiving apparatus is connected to one end of the second core 6 of the twin core section 4, the other end of core 6 being connected through a resistance 7 to a conductor in contact with the sea water, to furnish an earth connection. As shown, the resistance is connected to the cable armor wires 8 at point 9, a conventional grounding symbol being employed in the drawing to indicate that the armor wires are earthed. The core 6 together with the network 7 grounded at the point 9 constitutes a cable balancing return circuit, for instance of the type disclosed in Osborne Patent 1,390,580, September 13, 1921. Each of the cores 5 and 6, and also the core of the single-core cable section 3, may be of the nickel-iron alloy loaded type described and claimed in a patent to G. W. Elmen, 1,586,887, issued June 1, 1926, the cores being surrounded by insulation (not shown) and armor wires as usual.

The cable balancing return circuit being in balanced relation to the main cable with respect to the receiver, acts (as pointed out in the Osborne patent just mentioned) to greatly reduce the voltage appearing between the terminals of the main cable and the balancing sea earth as the result of extraneous electric fields acting upon the length of the twin core cable which lies in shallow water; and the sea earth is located at a depth beyond which the effect of electric waves of signaling frequencies employed in the cable is negligible. The length of the core 6 required to place the sea earth connected at an adequate depth may be considerable, as indicated by the dotted portion of the twin core cable section 4. In the case of a cable between New York and the Azores, for instance, it has been found advisable to use a sea earth core, about one hundred miles in length at the western end of the cable.

The circuit 10 may be, for example, a twin conductor or full metallic land cable having a length of the order of 15 or 20 miles, and comprising conductors 13 and 14, and exposed to inductive interference from electric railroad and power lines (not shown) which it parallels. The dotted portions of lines 13 and 14 are intended to indicate the considerable extent of circuit 10. The circuit 10 is balanced with respect to earth; that is, the

impedances to ground from the two sides 13 and 14 of circuit 10 are substantially equal and its conductors are also transposed in order to balance it with respect to magnetic fields.

The amplifier 2 is indicated as a four stage amplifier comprising vacuum tubes 15, 16, 17 and 18 in tandem. An input transformer for the amplifier is indicated at 20. Block 19 between the cable and transformer 20, and blocks 22 to 24 between the various stages of the amplifier, indicate any desired signal shaping networks or elements, for example those disclosed in my Patent 1,624,396, issued April 12, 1927. My Patents 1,586,970 and 1,586,972, both issued June 1, 1926, and British Patent 153,357 to Western Electric Company, Limited, also illustrate the application of shaping networks in a circuit similar to that in which the networks are here shown.

The tube 18 comprises an anode 25, a cathode 26 and a control electrode 27, and each of the other tubes of the amplifier has similar electrodes. A battery 30 supplies cathode heating current for the tubes, and space current is supplied to tubes 15 and 16 from a battery 35, to tube 17 from a battery 40, and to tube 18 from a battery 41 through a resistance 42 preferably of several thousand ohms, and a resistance 43. The resistance 43 is for straightening the grid potential plate current characteristic of the tube 18, to reduce distortion, and is preferably of the order of several hundred ohms, but may be omitted if desired. Conductor 13 is connected to a point on battery 41 at the same potential as that of the junction of conductor 14 with resistance 42 so that battery 41 will normally not send direct current through circuit 10.

Amplifier 2 may have a possible voltage amplification at some frequencies of the order of 25,000 times, and therefore should be earthed locally, or through a short sea earth cable of low impedance, to prevent oscillation troubles, since otherwise the amplifier may be unstable or tend to oscillate. However, if this earth connection were made by earthing the cathodes of the amplifier directly as is customary with vacuum tube amplifiers, the land cable 10 would be unbalanced, as one of its conductors 14 would be earthed directly through the amplifier. As this cable is exposed to strong fields from power lines and electric railways, this unbalance of its conductors to earth would cause voltages to appear at its terminals which might be of sufficient amplitude to seriously distort the telegraph signals.

To prevent undue disturbance caused by the tendency of the amplifier 2 to oscillate, and at the same time avoid unbalancing the circuit 10, the output of the amplifier when connected to the circuit 10 is shunted by two condensers 50 and 51 connected in series, and

the junction of the two condensers is earthed locally, or through a short sea earth cable of low impedance, as at 52, the capacity of the condensers being sufficiently small to avoid unduly shunting the circuit 10 with respect to the output of the amplifier at the signaling frequencies to be transmitted, yet sufficiently large so that the amplifier with its cathodes earthed through condenser 51 is sufficiently stabilized for the frequencies which would otherwise cause oscillation.

With the earthed condenser shunt the circuit 10 is still balanced. When the frequency range is that employed in a long submarine telegraph system, say from one-tenth of a cycle to a hundred cycles per second, and with a certain amplifier and land cable system, each of the condensers 50 and 51 might have a capacity of between 2 and 10 microfarads, a value of about five microfarads having been found suitable in one instance. However, the invention is not limited to the specific values mentioned in this description, as a certain reasonable proportion must be maintained between the impedance of the shunted condensers and the impedance of the circuits across which they are shunted in order to prevent the strength of the transmitted signals from being materially reduced.

In a system such as that described the natural capacities to ground of the batteries 30, 35, 40 and 45 are small in comparison to the capacity 51, and do not necessitate proportioning the capacities 50 and 51 relatively to each other to take account of that natural capacity, in maintaining the capacities to ground of the two sides of circuit 10 equal.

In Fig. 1 the amplifier input is connected to the submarine cable and sea earth by the transformer 20, the secondary winding of which is surrounded by an electrostatic shield 20' of copper, which is electrically connected to the terminal of the secondary winding that is connected to ground through condenser 51.

If, in the system of Fig. 1, the sea cable and its balancing return circuit were connected to the amplifier conductively, instead of through transformer 20, the impedance to earth of the conductor 14 of the land cable, in parallel with condenser 51, would be connected to core 6 of the sea cable through the common filament lead of the amplifier, while core 5 would be connected to the grid of the amplifier tube 15 through the shaping network 19. This would unbalance the twin core sea cable by shunting one conductor to earth by a capacity of the order of ten microfarads, the impedance to earth of the other conductor 5 being determined by the adjustment of the shaping network 19, but in general being higher than that of the circuit of conductor 6.

Similarly, the impedance to earth of the

sea earth conductor 6 of the sea cable would unbalance the land cable 10, as it would be directly connected to conductor 14 of the land cable, and connected to conductor 13 through a resistance of several thousand ohms.

In a system such as that of Fig. 1, the natural or inherent capacity to earth of the conductors 13 and 14 of the land cable 10 may be so large that it would, if the amplifier and the land cable were asymmetrically connected conductively to the sea cable and the sea cable balancing return circuit as referred to above, exert upon the balance to earth of the sea cable and the sea cable balancing return circuit a disturbing effect material in comparison to that which the cathode capacitative earthing connection at 52 would exert. The transformer between the sea cable and the amplifier prevents each of these disturbing effects, either of which would be serious.

Fig. 2 shows how the invention can be applied to connect the cable 1 to the input 25 of an amplifier 2', which may be similar to the amplifier 2 of Fig. 1 but without a transformer such as the transformer 20 of amplifier 2. To prevent undue disturbance resulting from the tendency of the amplifier 30 2' to oscillate, and at the same time avoid unbalancing the circuit 1, the input of the amplifier, when connected to the cable 1 is shunted by two condensers 70 and 71 connected in series, and the junction of the two 35 condensers is earthed locally, as at 72 or through a low impedance sea earth cable. A network 19' having the same general character and function as network 19 of Fig. 1 may be inserted between the grounded 40 capacitative shunt circuit 70, 71 and the amplifier 2'. The capacity of the condensers 70, 71 should be sufficiently large so that the amplifier 2' with its cathodes earthed through condenser 71 is sufficiently stabilized for the 45 frequencies which would otherwise cause oscillation. With the grounded condenser shunt the cable circuit 1 of Fig. 2 is still balanced, the grounded shunt in Fig. 2 being generally similar to that across the circuit 50 10 at the output of amplifier 2 of Fig. 1, and functioning similarly. The connections from the shunt 70, 71 to the grid and filament of the first tube of amplifier 2' may be conductive, no transformer such as transformer 20 of Fig. 1 being required in Fig. 55 2. In the latter figure, the circuit connecting the amplifier to the recorder is not a long cable circuit such as circuit 10 of Fig. 1, and does not afford a path, from the amplifier 60 cathodes to earth, of such low impedance as would unbalance the submarine cable.

This application is a continuation of my application Serial No. 58741, filed September 26, 1925, entitled "Electric current transmission", as to subject matter.

What is claimed is:

1. An electric space discharge device having an anode element, a cathode element and an impedance control element, a circuit having its two sides connected respectively to 70 the cathode element and to one of the others of said elements, and similar impedances connected in series relation across said circuit, said cathode element being connected to earth through at least one of said similar 75 impedances and only in such manner that the sides of the circuit are balanced with respect to said earth.

2. The combination set forth in claim 1, said circuit being of considerable length and 80 said similar impedances being located at one end only of said circuit.

3. A system according to claim 1 for transmitting signal currents, said similar impedances having such values as to shunt from 85 said circuit and said device a small part only of the currents of signaling frequencies.

4. An amplifying system comprising an electric space discharge device having an anode element, a cathode element and an 90 impedance control element, a circuit having its two sides connected respectively to the cathode element and one of the others of said elements, and similar impedances in series relation across said circuit, said cathode element being connected to earth through at least one of said similar impedances and only in such manner that the sides of the circuit are balanced with respect to said earth, and each of said similar impedances having such 95 value as to prevent oscillations from being set up in said amplifying system.

5. A system according to claim 4, said similar impedances consisting principally of 100 capacitative reactance.

6. A system according to claim 4, said similar impedances consisting principally of capacitative reactance and having such 105 values as to shunt from said circuit and said device a small part only of currents of frequencies from zero to several hundred cycles per second.

7. A system according to claim 4 for transmitting signals between the discharge device as one unit and the circuit as another 115 unit, said similar impedances consisting principally of capacitative reactances the combined impedance of which is several times as high as the impedance at signalling frequencies of the unit into which the signals are being transmitted.

8. A system according to claim 4 for transmitting signals between the discharge device as one unit and the circuit as another unit, said similar impedances consisting principally of capacitative reactances the combined impedance of which is several times as high as the impedance at signalling frequencies of the unit from which the signals are being 120 transmitted.

9. A low frequency telegraph system comprising a long submarine telegraph cable, a second telegraph circuit, balanced as regards the impedances of its two conductors to earth and subject to interference from extraneous electrical fields, and means including an electric space discharge amplifying device composed of direct amplifying units only connecting said cable to said circuit and maintaining the balanced condition of said circuit, said means transmitting low frequency telegraph signals between said cable and said circuit, the impedance to earth of said cable being such that it would materially disturb the balanced condition of said circuit were said circuit conductively connected to said cable through said discharge device.

10. A signaling system comprising a submarine cable, a cable balancing return path therefor, an electric space discharge receiving amplifier associated with said cable and said return path and having an anode and a cathode, a receiving instrument, a circuit of substantial length having one of its two conductors connected to said cathode and its other conductor associated with said anode, said circuit connecting said amplifier and said receiving instrument, similar impedances connected in series relation across said circuit, said cathode being connected to earth through at least one of said similar impedances and only in such manner that the two sides of said circuit are balanced with respect to said earth, and said circuit having inherent impedance to earth at least as small for frequencies of the signaling frequency range, as a value of the order of the value of said similar impedances, and means for preventing said receiving instrument connecting circuit from adversely affecting said cable balancing path in its function of minimizing voltages induced by electrical fields extraneous to the cable.

11. In a signaling system, a submarine cable, a cable balancing return circuit, a receiving amplifier associated with said cable and return circuit, a receiving instrument, a metallic circuit of substantial length connecting said amplifier and said receiving instrument, and signal repeating means for preventing said receiving instrument connecting circuit from adversely affecting said cable balancing circuit in its function of minimizing voltages induced by electrical fields extraneous to the cable.

12. A low frequency telegraph system comprising a long submarine cable conductor, a return path therefor balancing the impedance of said cable conductor, and including a conductor which is earthed at sea and parallels said cable conductor to reduce the voltages induced by interfering electrical fields to which the shallow water section of said cable conductor may be subjected, a low frequency telegraph circuit

whose conductors are balanced both as regards their impedance to earth and their exposure to extraneous magnetic fields, and means comprising an electric space discharge amplifying device, connecting the cable conductor and its return path conductor to said telegraph circuit and maintaining the impedance balance between the cable conductor and its return path, said means transmitting low frequency telegraph signals between said circuit and said conductors, and the impedance, to earth, of said circuit being such that it would materially disturb said impedance balance of said cable conductor and its return path were said circuit connected conductively to said cable conductor and said return path conductor through said discharge device.

13. A submarine cable signaling system comprising a long submarine cable conductor, an electric space discharge receiving amplifier therefor having its cathode or cathodes earthed through an impedance sufficiently small to prevent the amplifier from oscillating, a balancing return path for said conductor, simulating the impedance of said conductor and including a conductor which is earthed at sea and parallels said cable conductor to reduce the voltages induced by interfering electrical fields to which the section of the cable lying in shallow water may be subjected, a receiving circuit fed from said amplifier and balanced as regards the impedances of its two sides to earth, said circuit being exposed to interference from extraneous electric fields, the impedance, to earth, of said circuit being such that it would exert upon the impedance balance of said cable conductor and its return path a disturbing effect of magnitude material in comparison to any due to said cathode earthing impedance, were said circuit connected conductively to said cable conductor or said return path through said amplifier, and the impedances to earth of said cable conductor and said return path being such as would materially disturb said balanced condition of said circuit were said circuit connected conductively to said return path or said cable conductor through said amplifier, and means connecting said cable conductor and said return path to said amplifier and preventing the impedance balance between said cable conductor and its return conductor from being disturbed by either said circuit or said cathode earthing connection, and preventing said balanced condition of said circuit from being disturbed by said cable conductor and said return path.

14. A system according to claim 10, said similar impedances having such values as to shunt from said circuit a small part only of the currents of signaling frequencies.

15. A system according to claim 10, said

similar impedances consisting principally of capacitative reactance.

16. A system according to claim 10, said similar impedances consisting principally of 5 capacitative reactance and having such values as to shunt from said circuit a small part only of currents of frequencies from zero to several hundred cycles per second.

17. In combination, an electric space discharge amplifier, means for transmitting low frequency telegraph signals thereto, said means comprising a cable and a cable balancing return circuit therefor, said cable balancing return circuit comprising means 15 for diminishing the effects of extraneous interfering electric waves to which the receiving end of the cable may be subjected, said last means comprising a conductor adjacent to and paralleling the conductor of the cable 20 and extending from the receiving end of the cable to a sea earth so far removed from the receiving end of the cable that the remainder of the cable will be in water of such depth that the effect of said extraneous 25 waves will be negligible, and said amplifier having a cathode or cathodes, and a connection to earth from said cathode or cathodes, the impedance of the latter connection being so low that it would be capable of 30 substantially lessening said reduction of in-

terference effects if said amplifier were connected conductively to said cable and its balancing return circuit, and said first mentioned means comprising means preventing said cathode earthing connection from so disturbing the balance to earth of said cable and its balancing return circuit as to disturb 35 said functioning of said balancing return circuit in reducing interference effects.

18. In combination two two-conductor 40 cables the impedance to earth of whose conductors is balanced, a space discharge amplifier connecting said cables and means for preventing either of said cables from unbalancing the other and at the same time 45 effectively earthing the amplifier cathode or cathodes for the purpose of preventing the amplifier from oscillating, said means comprising two condensers in series bridged across the junction between one set of amplifier terminals and the two-conductor circuit to which said terminals are connected, the junction of said condensers being connected to an earth conductor of low 50 impedance.

In witness whereof, I hereunto subscribe my name this 1st day of December, A. D. 1925.

AUSTEN M. CURTIS.
